UNITED STATES PATENT OFFICE

WILLIAM HENRY KITTO, OF FERNDALE, MICHIGAN

RADIORECEIVER

Application filed June 10, 1925. Serial No. 36,125.

This invention relates to radio circuits or hookups employing vacuum tubes, wherein considerable trouble is often experienced in preventing the oscillation of such tubes which is a frequent source of trouble in many types of hookups, especially cascaded radio frequency circuits, greatly interfering with tuning and reception and otherwise adding difficulties to the proper operation of the receiver.

As the circumstances under which such oscillation occurs is generally appreciated by those versed in the art to which this invention appertains, although the fundamental reasons for the phenomena may be in some respects obscure, as is the case with most electrical phenomena, particular relation of the conditions resulting in oscillation is not dwelt on extensively herein.

The object of the invention is to secure in a simple and effective manner the stabilizing of radio frequency circuits so that the tendency of the tubes to oscillate may be minimized and easily brought under control; the invention further contemplating the introduction of a novel method of controlling the polarity of the filament lead connected with the grid return of the first or any of the tubes of a radio frequency circuit normally subject to oscillation for the purposes hereinafter stated.

A further object of the invention is to include in such a circuit a lamp or vacuum tube, the filament of said tube being shunted across the filament of the radio frequency tube, the oscillation of which it is desired to control, a resistance being incorporated between the filaments of the said two lamps or tubes and a variable contact establishing communication between the said resistance and a rheostat controlling the filament current of the radio frequency tube or tubes employed in the circuit.

The invention further aims, where the additional stabilizing tube is in the form of a

three element vacuum tube to connect the grid of the stabilizing tube to the grid of the tube being stabilized, and to connect the plate of the stabilizing tube with the positive B-battery line.

Still further objects subsidiary to or resulting from the aforesaid objects or from the construction or operation of the invention as it may be carried into effect, will become apparent as the said invention is hereinafter further disclosed.

In carrying the said invention into effect, I may provide in a radio frequency circuit having, say, two stages of radio frequency amplification arranged in cascade formation wherein one of the filament leads of the radio frequency tubes are each connected to the positive A-battery supply and the other filament leads to the negative A-battery supply through a rheostat, a stabilizing tube having a filament shunted across the leads of the filament of the first radio frequency tube with a variable resistance interposed between that lead which is not connected to the A-battery supply and the said stabilizing tube, the adjustable contact of said variable resistance being the means establishing connection with the said rheostat, the filaments of the stabilizing tube and the said first radio frequency tube being connected together and the plate of the said stabilizing tube being connected to the positive B-battery supply.

All of which is more particularly described and ascertained hereinafter, by way of example, having reference to the accompanying drawing, wherein—

Figure 1 illustrates schematically a radio frequency circuit embodying the said invention;

Figure 2 illustrates a modified form of the same;

Figure 3 is a fragmentary view of the diagram, Figure 1, illustrating a somewhat modified wiring of the stabilizing tube circuit;

Figure 4 illustrates a further modified form of hookup, and

Figure 5 illustrates a similar hookup to that shown in Figure 4, embodying six-element tubes.

Similar characters of reference indicate similar parts in the several figures of the drawings.

In the arrangement shown in Figure 1, the principles of this invention are applied in a very simple and effective manner, which has proved itself very efficient in actual practice in a circuit having two stages of radio frequency amplification arranged in cascade.

In this case 1 indicates the first radio frequency amplifying tube, and 2 a second tube, 3 being the detector tube of the circuit. Following a common practice in circuits such as that shown, the grid 4 of the tube 1 is connected by the grid lead 5, through an inductance coil 8 and grid return 5^a with the negative terminal 6 of the filament 7 of the said tube, and the plate 9 of the said tube is connected with the primary 10 of an inductance 11 of the positive B-battery supply 12. The positive A-battery supply 13 is connected to the positive filament terminal 14 of the said tube 1. 15 is a rheostat controlling the amount of current passed through the filaments of the tubes 1 and 2. So far there is nothing unusual about the circuit described.

Oscillation of the tubes in such radio frequency circuits is often difficult of control, especially when two or more stages of radio frequency amplification are employed, and I propose to minimize and control such oscillation by the incorporation in the circuit of a stabilizing tube 16, which may be simply a vacuum tube similar in all respects to the tube 1, and connect the negative terminal 17 of the filament 18 of this stabilizing tube with the negative terminal 6 of the filament 7 through the medium of a stabilizing rheostat 19 which includes an adjustable contact 19^a connected to the out-put end of the said rheostat 15. The ends of the resistance of the said stabilizing rheostat are numbered 21 and 22 for the sake of easier identification in the description following.

The positive terminal 20 of the stabilizing tube is connected to the positive A-battery supply 13 so that the filament of the stabilizing tube may be said to be shunted across the leads of the filament of the radio frequency tube 1, or, in other words, across the grid return 5^a and the A-battery supply.

The resistance of the rheostat 19 is preferably of such value that it may cut down the flow of current through one or other of the filaments 7 or 18 until either one is barely luminous when the adjustable contact 19^a of the rheostat is moved to one or other end thereof, and it will be apparent that in an intermediate position of the said contact both the filaments of the tube 1 and the stabilizing

tube 16 will burn with equal brilliancy of an intensity governed by the filament-rheostat 15, which may be regulated to suit the best receiving conditions. However, if the said contact 19^a be moved to the end 21 of the resistance of the stabilizing rheostat 19, the filament of the stabilizing tube 16 will be cold, or approximately cold. Hence, with this setting, the grid return at the terminal 6 will be of negative polarity and of its greatest negative potential permitted by the setting of the filament rheostat 15, and the lead connected to the terminal 17 of the stabilizing tube of positive polarity, due to the interposition of the resistance of the rheostat 19 between it and the negative current supply from the said filament rheostat 15.

Should the radio frequency tubes tend to oscillate in an undesirable manner, they may be readily stabilized by reducing the negative polarity of the grid return which is accomplished by moving the contact 19^a of the rheostat 19 toward the end 22 thereof, which reduces the temperature of the filament 7, at the same time raising the temperature of the filament 18 of the stabilizing tube, and if the rheostat be of sufficient resistance and the adjustable contact be moved to the said end 22 thereof, the said filament 18 of the stabilizing tube would burn at the full brilliancy permitted by the rheostat 15, and the filament 7 would become practically cold, whereupon the grid return will be of positive polarity and the lead connected to the terminal 17 of the stabilizing tube of negative polarity, due to the fact that the resistance of the rheostat 19 is now interposed between the negative current supply and the terminal 6 of the filament 7.

It will be obvious that the negative or positive potential at the said terminal 6 will therefore be varied relatively, or reversed, according to the adjustment of the contact 19^a, and it will also be apparent that the rheostat 15 controls the volume of current supplied to both the amplifying tube and the stabilizing tube, no additional current is consumed by the application of the stabilizing tube to the circuit in the manner described.

The stabilizing tube may be one which has lost its usefulness other than that the filament has not been burned out, in which case only the filament may be employed in the circuit as hereinbefore set forth, but where the tube is still capable of operation as an amplifier or rectifier, I prefer to couple the grid 23 thereof to the grid 4 of the amplifying tube 1 and to connect the plate 24 of the stabilizing tube with the B-battery supply 12 as shown in said Figure 1, whereby the said stabilizing tube tends to also impress a stabilizing current in the primary 10 of the inductance 11.

If the rheostat 15 in Figure 1 is "turned up" or adjusted to a point which raises the

temperatures of filaments 18 and 7 so that together they emit electrons at as great or a slightly greater rate than the plate potential can attract them through the anodes 24 and 9, the plate current flow between the said anodes and the said filaments is limited to a specific amount, and if the filament 7 is raised to a higher temperature than 18, by adjusting arm 19^a toward 21, then the plate current flow 5 will be greater from the anode 9 to filament 7 than from anode 24 to filament 18, and therefore more "B" current will flow from line 12 through coil 10 to anode 9 than from line 12 to anode 24. Inversely and with the rheostat 10 15 still in the same position, if the temperature of filament 18 is raised and that of filament 7 lowered by adjustment of arm 19^a, then the plate current flow will be greater from anode 24 to filament 18 than that from anode 9 to filament 7, and consequently more 20 plate or "B" current will flow from line 12 to anode 24 than from line 12 to anode 9 through coil 10, thus controlling the strength of the oscillations through coil 10.

25 The arrangement shown in Figure 2 is similar in all respects, except that an incandescent lamp 25 has its filament 26 shunted across the grid return 5^a and the A-battery supply in place of the vacuum tube 16 shown 30 in the first figure, the said incandescent lamp being of practically the same amperage as the amplifying tube 1, and the operation in controlling the polarity of the current return is effected in the manner already 35 described.

40 In Figure 3 the arrangement shown in Figure 1 is simply modified by the connecting of the grid return 40 of the secondary coil 11^a of the inductance 11 by a wire 27 to the negative terminal 6 of the first amplifying tube, so that the polarity of the said grid return 40 is also varied and in the same manner as the polarity of the grid return 6. This arrangement is preferred where more than two 45 stages of radio frequency amplification are employed, although it is also very successfully applicable where there are only two stages of radio frequency amplification. The said arrangement, Figure 3, also differs 50 from Figure 1 in that the plate 24 of the stabilizing tube is connected to the same end of the primary 10 as the plate 9 of the first amplifying tube 1. This operates to assist in the impressing of weak signals on the said 55 primary 10 and requires a greater movement of the contact 19 to effect stabilizing, but for general purposes of reception the arrangement of the plate leads as shown in Figure 1 is preferred.

60 In Figure 4, the second amplifying tube 2 is indicated as being individually provided with a further stabilizing tube 28 associated therewith in the same manner as the stabilizing tube of the first amplifying tube, 29 being an additional stabilizing rheostat, 30 the

movable contact thereof, 31 the grid return, and 32 and 33 the filaments of the stabilizing and amplifying tubes of the second stage respectively.

65 In Figure 5 the circuit is identical with Figure 4, except that separate amplifying tubes are not used but six-element vacuum tubes 34 and 35 employed for both the first and second stages of radio frequency amplification, the filaments 36 and 37 of the tube 34 serving in the same manner as the filaments 7 and 18 of the tubes 1 and 16, and the filaments 38 and 39 serving as the filaments 33 and 32 of the tubes 2 and 28 of the second stage shown in Figure 4.

70 The inclusion of a stabilizing tube or tubes in a radio frequency circuit along the lines suggested herein greatly facilitates proper operation of a radio receiver both as to stabilizing of the operation of the amplifying 75 tubes and control of volume, so that signals of greatly varying intensity may be reproduced with a minimum of distortion and freedom from extraneous noises due to improperly stabilized radio frequency amplifying tubes.

75 Due to the great number and variety of circuits to which such an arrangement is applicable and the many types of tubes and lamps available for employment, the invention admits of being carried into effect in many ways without departing from the essential features thereof, and it is, therefore, desired that the specification be read as being merely illustrative and not in a limiting 85 sense, except as necessitated by the prior art.

80 What I claim is:—

90 1. In a radio circuit having more than one stage of amplification including an amplifying tube, an output inductance in its circuit, the plate of the amplifying tube of one of said stages being connected with its output inductance, stabilizing means comprising a stabilizing tube similar to said amplifying tube having its filaments shunted across the 95 filament leads of said amplifying tube, means for variably changing and reversing the potential and polarity of the filaments of said amplifying and stabilizing tubes relative to one another, the grids of said tubes being coupled together and having a common return to the filament of said amplifying tube, and the plate of said stabilizing tube being connected to said inductance.

100 2. In a circuit comprising an input inductance, an output transformer and an amplifying tube, an additional tube having a filament shunted across the filament leads of said amplifying tube, a rheostat interposed between the negative leads of said tubes, a 105 movable contact cooperating with said rheostat, a source of "A" current supply, said contact being connected to the negative terminal of said source, the grids of each tube being connected to one end of said input in-

115

ductance, the other end of said input inductance being connected to the negative lead of said first named amplifying tube, the plate of said amplifying tube being connected to one end of the primary winding of said output transformer, a source of "B" current supply, the other end of said output transformer being connected to the plate of said additional tube and to the positive terminal of said source of "B" current supply.

In testimony whereof I affix my signature.
